UNITED STATES PATENT OFFICE.

ANDREW D. ROCKWOOD, OF WEED, CALIFORNIA.

GOLF GAME.

Application filed June 16, 1927. Serial No. 199,322.

This invention is a game apparatus by the use of which an indoor game may be played closely simulating the game of golf. The invention provides a simple and inexpensive apparatus whereby all the plays which develop in the game of golf may be simulated, the nature of the play being determined by chance. The invention provides a representation of a golf field and includes elements representing clubs, and the strokes made by the use of the several clubs, and also includes markers or devices whereby the position of the ball along the fairway or the green may be indicated as determined by the action of the club elements. The invention is illustrated in the accompanying drawings and will be hereinafter fully described, the novel features being particularly pointed out in the appended claims.

20 In the drawings:

Figure 1 is a plan view of a game board embodying the invention;

Fig. 2 is a longitudinal vertical section of the same;

25 Fig. 3 is a detail view illustrating markers which may be employed, and

Fig. 4 is a detail view illustrating the game elements which represent clubs.

In carrying out the invention, there is 30 provided a board 1 which may be supported upon feet 2 of any approved form and upon the upper surface of this board are representations of fairways corresponding to the fairways laid out upon a golf course, the drawings indicating a nine hole course. 35 These fairways are indicated by the reference numeral 3, and it will be noted that they are of various lengths and each comprises a clear path 4, a green 5, a tee 6 and transverse lines 7 having numbers 8 at their 40 ends along the margins of the respective diagrams so that the yardage or distance through which the ball is moved may be easily calculated. Beyond the green, there is on each diagram the word "Lost", as shown at 9, the significance of which will hereinafter appear. Along the center of each diagram is the clear path 4, as previously stated, and in each path are suitable 45 legends indicating the number of the tee, the distance from the tee to the green and par play for the particular hole indicated. The green may be circular or given any other approved outline, these particular outlines being of no special significance in playing the game but lending an ornamental

and attractive appearance to the board. At the center of the board is an opening 10 around which a rim 11 is secured upon the top of the board and below which a platform 12 is secured to the under side of the board. This opening is preferably circular, as shown, and at the center thereof a post 13 is erected upon the base or platform 12, as shown clearly in Fig. 2. This post 15 constitutes the support for a wheel or turntable 14 which is dished slightly, as shown at 15 in Fig. 2. A hub sleeve 16 is secured in the wheel at the center thereof and fits over the post 13, a bearing 17 being provided 20 at the upper end of the hub to rest upon the upper extremity of the post and permit the wheel or turntable to rotate about the post with minimum friction. The hub member is provided at its upper extremity 25 with a head 18 which may be milled in order that it may be easily grasped and spun to impart the desired rotation to the wheel. Fitted between an annular flange 19 on the hub member and the top of the wheel is a 30 disk 20 in the annular edge of which are formed vertical notches or pockets 21, this disk or pocket member being very firmly secured to the wheel and to the hub member, as will be understood upon reference to Fig. 35 2. At one point in the rim 11, a slight projection 22 is provided on the inner periphery thereof so that the balls which represent clubs will be deflected toward the hub instead of running solely around the inner 40 periphery of the rim under centrifugal action. The upper surface of the wheel 14 is divided by radial lines 23 and by circles 24 into a plurality of spaces in each of which are marked numbers or words indicating yardage or some result which is common in the game of golf. The radial lines 23 are spaced equi-distantly around the wheel and the annular spaces defined by the circles 24 are differently colored, the colors indicated upon the drawings and those which are preferably used being as follows 45 reading from the outer circle toward the hub, red, green, yellow, blue and white. The innermost white circle bears the letter "O" 50 upon alternate spaces, the remaining spaces being blank but the other circles have no blank spaces, either a number or a letter or word being displayed in each space of the outer four circles. I also provide a plurality of balls or spherical objects 25, 26, 27, 28 and 29, indicated in Fig. 4, which may be 55

marbles or small rubber balls or other spherical objects, the several objects being distinctively colored and each bearing a color corresponding to the color of one of the circular spaces on the wheel. These rolling objects represent the different clubs used in the game of golf and are located upon the wheel by chance to indicate the yardage or other scoring result to which a 10 player is entitled.

There are also provided markers 30, shown in Fig. 3, which may be of any approved design and are numbered so that they may be distinguished, the numbers representing 15 players participating in the game.

The colors upon the rolling objects and upon the turntable or wheel designate different golf clubs, the red ball or circle indicating a wood club, the green ball or circle 20 representing the mid-iron, the yellow ball or circle representing the mashie, the blue ball or circle representing the niblick and the white ball or circle representing the putter. In playing the game, the player having the 25 honor at the first tee will spin the wheel and drop the red ball thereon. When the wheel comes to rest, the ball will be seated in one of the pockets 21 in the edge of the disk member 20 and the player will then score 30 according to the legend appearing upon the red circle in the same segment or radial column at the foot of which the ball lies. Assuming that the legend at the outer end of the column at which the ball is seated is 250, 35 the player puts his marker on the fairway at the 250 yard line. Each player, in turn, will spin the wheel and drop the red ball thereon in the same manner and then the players, in turn, will use the other balls in 40 like manner according to the position of their respective markers. The red ball, which represents a wood club, may be used for any distance but the green ball, which represents a mid-iron, must never be used 45 for a distance over two hundred yards, the use of the yellow ball or mashie being restricted to a distance of one hundred and fifty yards or under, while the blue ball or niblick is not used for over fifty yards. The 50 white ball or putter should never be used until the player has reached the green. It will be noted that in the segments of circles upon the wheel or turntable appear the legends "Miss", "Lost", "Out", "On", "O", 55 which mean, respectively, that the player has missed and lost one stroke, has lost a ball and suffers a penalty of one stroke, has gone out of bounds and is penalized one stroke, is on the green and may use the putter, and is in the cup.

The legend "Lost", indicated at 9, at the extreme end of each fairway and beyond the green has no playing connection with the same legend on the wheel but is intended only as a safety valve and trap for the

player who would use a wooden club in the wrong place. Should the yardage obtained at any time take the player to this area, he would place his marker accordingly and after taking a penalty of one stroke play 70 back toward the green from his marker. The markers are provided to help in counting distance only and the numbers thereon are only to identify the player. Should the ball at any time hang on the point between 75 two pockets 21 in such a manner that it cannot be readily decided which division contains the greater portion of the ball, the player is entitled to take another spin or stroke without penalty. Score cards may 80 be provided although the particular form of score card is not a part of the present invention. Any kind of golf that may be played on a regular golf course may be played with this apparatus but the rules as 85 to distance for the several clubs must be strictly followed. The apparatus is very simple and inexpensive but will provide entertainment for golf players which may at 90 times become as exciting and intense as the game actually played upon a golf field.

It will be understood, of course, that the invention is not limited to the particular arrangement of greens illustrated but the greens may be arranged in simulation of 95 any golf course, or otherwise, as may be preferred.

Having thus described the invention, I claim:

1. A game apparatus comprising a game board having a representation of a golf course thereon, a wheel rotatably mounted in the board and having legends thereon designating golf plays, said legends being arranged in concentric circles each of which has a distinctive color, and a plurality of balls adapted to roll over the wheel through spinning of the wheel and come to rest in a chance location thereon to determine a play, each ball bearing the same color as one of the circles on the wheel, and means near the center of the wheel for retaining the ball in the position of rest.

2. A game apparatus comprising a game board having a representation of a golf course thereon, a wheel mounted for rotation in the board and having its upper surface divided into a plurality of concentric circles each distinctively colored and radial columns intersecting the circles and further provided with designations in the several columns and circles indicative of golf plays, a plurality of balls to rest upon the wheel and be caused to travel thereover by spinning the wheel, each ball bearing the same 125 color as one of the circles on the wheel, a circular series of pockets on the wheel near the center thereof, each pocket being aligned with one of the radial columns on the wheel, and means adjacent the edge of the wheel 130

to deflect a rolling ball toward the pockets.

3. A game apparatus comprising a game board having a representation of a golf course thereon, a wheel mounted for rotation in the board and having a plurality of concentric circles inscribed upon its upper circle, each surface being distinctively colored and bearing legends indicative of golf

plays, and a plurality of rolling objects adapted to travel over the wheel through spinning of the wheel and come to rest near the center thereof and each bearing the same color as one of the circles on the wheel. ¹⁰

In testimony whereof I affix my signature.

ANDREW D. ROCKWOOD.
